ELECTROMECHANICAL TIMER

Lawson E. Richtmyer, Silver Spring, Md., and Paul G. Gerhard, Palmetto, Pa., assignors to the United States of America as represented by the Secretary of the Army

Application May 10, 1955, Serial No. 507,519

1. Claim. (Cl. 161—1)

(Granted under Title 35, U.S. Code (1952), sec. 266)

The invention described herein may be manufactured and used by or for the Government for governmental purposes without the payment to us of any royalty thereon.

This invention relates to timers, and particularly to an electromechanical timer.

One object of this invention is a new and novel variable speed electromechanical timer.

Another object is a new and novel escapement means for an electromechanical timer.

Another object is a new and novel method of varying the speed of an electromechanical timer.

A further object is a self-energizing timer adaptable for prolonged operation.

The specific nature of the invention as well as other objects and advantages thereof will clearly appear from the following description and drawing wherein:

Figure 1 is a schematic mechanical diagram of the invention.

Figure 2 is an enlarged schematic diagram of the escapement and escapement actuating means, at the half-cycle position.

Figure 3 is a view similar to Fig. 1 wherein the escapement is at a position beyond the half-cycle position.

Figure 4 is a schematic diagram of the electrical system of the invention.

A preferred embodiment of the invention combines a novel mechanical escapement and escapement actuating means. Referring to Fig. 1, the escape wheel 10 is provided with a plurality of beveled teeth indicated generally by numeral 11, the teeth being equally spaced about the periphery of the wheel as at 11a, 11b, 11c, etc. The teeth are beveled in the direction of travel of the wheel, counterclockwise as seen in the drawing. The oscillating pallet member 12 of the escapement has a pair of pallet pins 13a and 13b adapted to cooperate with the teeth 11 of wheel 10. These pallet pins are located upon member 12 in a particular relationship to pivot 14 and teeth 11 in a manner described hereinafter. Arm 15 depends from member 12.

Wheel 10 is a part of a gear train indicated generally by numeral 16. Pinion 17 of gear train 16, which is adapted to rotate with wheel 10, engages gear 18. Pinion 19, which turns with gear 18, engages gear 20. Pinion 21, which turns with gear 20, engages gear 22. And pinion 23, which turns with gear 22, engages gear 24. Gear 20 and pinion 21 are stripped of somewhat less than half of their teeth. The remaining teeth of each member are located on diametrically opposite sides of the combined gear and pinion.

Spiral spring 25 biases gear 24 in the counterclockwise direction, gear 24 adapted to drive the remainder of gear train 16. Gear 24 has arm 26 affixed thereto, said arm adapted to actuate switch lever 27 to cause the lever to move to position 27a in contact with terminal 28, thus, closing an electrical circuit, not shown. Electric leads 29 connect lever 27 and terminal 28 with the circuit to be

2

closed. Torsion spring 30 urges lever 27 to move clockwise to its functioned position shown at 27a. Grounded leaf spring 31 normally restrains switch lever 27 from moving to its functioned position.

5 Numeral 32 indicates an electromagnet which is connected electrically with an energizing unit such as relaxation oscillator 33, the components of which are shown in Fig. 4.

It is understood that other electromechanical transducers such as piezoelectric means can be employed in lieu of the electromagnet.

The energizer which comprises a battery 34, Fig. 4, has a current limiting device such as a rheostat, constant current ion chamber, or variable resistor 35 in series therewith. A capacitor 36 is connected across the battery and resistor, and a diode 37 and electromagnet 32 are connected in series and are placed in parallel with the capacitor. Normally, a variable current limiting device and a variable capacitor are employed.

20 A magnetically sensitive armature 38, pivoted at 39, is adapted to act against arm 15 of pallet member 12 as the armature rotates clockwise under the attraction of electromagnet 32.

Depending upon the parameters of the various circuit elements in Fig. 4, capacitor 36 will be charged by battery 34 through resistor 35 and then discharged through diode 37 and electromagnet 32 at a predetermined repetitive rate. At each discharge, electromagnet 32 is energized and attracts armature 38 thereto. Armature 38, in turn, 30 acts against arm 15 of pallet member 12 to cause the member to rotate counterclockwise a few degrees about pivot 14.

Escape wheel 10 is driven by spring 25 through gear train 16 so that, when arm 15 is moved by armature 38 35 wheel 10 advances a distance equal to the thickness of one tooth. Theretofore, wheel 10 had been restrained by the engagement of tooth 11b and pallet pin 13a. Almost immediately the beveled portion of tooth 11d engages pallet pin 13b, as seen in Fig. 2. As tooth 11d 40 moves relative to pallet pin 13b, pallet member 12 is caused to pivot at 14, arm 15 returning to its original position as seen in Fig. 3. At the same time armature 38 is returned to its original position by arm 15. Wheel 10 continues to rotate counterclockwise until its motion is once more arrested, this time by the engagement of 45 tooth 11a with pallet pin 13a. The escapement then awaits another pulse from electromagnet 32, at which time the cycle is repeated.

It will be noted that pallet pin 13a is so located with respect to pivot 14 as to engage the leading edge of a tooth 11 and to thereby lock the escapement against further movement. Pallet pin 13b is located with respect to pivot 14 so that any tooth 11 tends to rotate the pallet member 12 in a clockwise direction to urge pin 13a to follow a direction toward the root circle of wheel 10 to 55 ultimately be engaged by a tooth 11. The principal element tending to rotate pallet member 12 counterclockwise is armature 38.

Each time capacitor 36 discharges, escape wheel 10 60 advances a distance equal to the distance between the leading edges of two adjacent teeth. The system can be adjusted to obtain a rapid repetitive rate such as one discharge per second, a slow repetitive rate such as one discharge per month, or any other repetitive rate by adjusting resistor 35 and/or capacitor 36, the only limitation being the capabilities of presently available electrical components. Thus means are provided for regulating the rotational speed of the escape wheel at variable rates.

Once in operation, the system continues to function until the teeth of gear 20 "run out" with respect to pinion 19. Almost immediately thereafter, the teeth of pinion 21 "run out" with respect to gear 22. At that

point the escapement has no more influence on the speed of rotation of gear 24. Gears 22 and 24 spin without restraint under the urging of spring 25. Arm 26 engages switch lever 27 causing the lever to move in the clockwise direction beyond the influence of leaf spring 31. Spring 30 takes over thereafter to move lever 27 to position 27a in contact with terminal 28, closing the electrical circuit, not shown.

It will be understood that the spring energy consumed in driving gear train 16 to the functional position is only a small fraction of the spring energy available. The remainder is available for doing work such as moving a weight or linkage.

It will be understood also that the electromechanical timer is, in essence, a digital counter, the total elapsed time from initiation to function of the timer being the number of counts multiplied by the time lapse between counts. Inasmuch as one count is equal to one pulse of the electromagnet, the timer can be preset or advanced any desired amount by the preinitiation application of the appropriate number of pulses.

It will be apparent that the embodiment shown is only exemplary and that various modifications can be made in construction and arrangement within the scope of the invention as defined in the appended claim.

We claim:

In combination: an escape wheel mounted for spring-biased rotation about a first pivot, a series of teeth spaced-apart around the periphery of said wheel, each tooth being formed with substantially parallel leading and trailing edges, the leading edge of each tooth being shorter than the trailing edge so that the extremity of each tooth is at an angle with respect to either tooth edge, spring-biased rotation of said wheel being in a direction from the trailing to the leading edge, a pallet mounted for rotation about a second pivot, a pallet actuating means adapted to drive said pallet, said pallet actuating means comprising, a magnetically sensitive armature having one end pivotally fixed and the other end free for pivotal movement, an electromagnet positioned adjacent said armature and adapted to attract the free end of said armature upon electrical pulsing of said electromagnet, a capacitor in circuit with said electromagnet, electronic circuit means including a battery and a diode adapted to discharge said capacitor at a predetermined repetitive rate, said electromagnet adapted to attract said free end of said armature at said predetermined repetitive rate in response to the pulsing of said capacitor, an arm depending from said pallet and extending to contact said free

end of said armature so that said armature drives said arm in the direction of spring-biased rotation of said wheel upon discharge of said capacitor, upper and lower pins at the end of said pallet nearest said wheel, said upper pin located above an axis extending through said first and second pivots, said lower pin located below said axis, the radial distance from said second pivot to the upper pin being substantially greater than the radial distance from said second pivot to the lower pin, the upper pin initially engaging said leading edge of a tooth of said wheel in the absence of an electrical pulse from said capacitor so as to prevent rotation of said wheel and urge said arm against said armature, said electromagnet receiving an electrical pulse from said capacitor only for a duration sufficient to cause said armature to drive said pallet a large enough distance to move said upper pin out of locking engagement with said leading edge of said tooth thereby freeing said wheel for rotative movement, said lower pin being positioned so that when said wheel rotates after being unlocked the extremity of a tooth pushes against said lower pin and causes said arm of said pallet to rotate in a direction opposite to that of wheel rotation, the rotation of the pallet thus caused again forcing said upper pin into locking engagement with the leading edge of a successive wheel tooth and at the same time restoring the arm of the pallet to its initial position in contact with said armature, the combined action of the pulsed actuating means and the pallet pins engaging the teeth of said wheel then continuing to intermittently rotate said wheel one tooth distance for each electrical pulse applied to said electromagnet by said capacitor.
